UNITED STATES PATENT OFFICE.

GEORGE HUNT LAMB, OF LONDON, ENGLAND.

LOCK.

1,104,052.

Specification of Letters Patent. Patented July 21, 1914.

Application filed November 22, 1913. Serial No. 802,490.

To all whom it may concern:

Be it known that I, GEORGE HUNT LAMB, a subject of the King of Great Britain and Ireland, residing at London, England, have 5 invented Improvements in Locks, of which the following is a specification.

This invention relates to a padlock or other lock of the type having a gapped ring forming the shackle which is secured by a 10 bolt shot into engagement with the gap.

The invention consists in an improved construction whereby a lock of this type is made to lock automatically when the ring is turned into the position in which the gap 15 is in register with the bolt.

The accompanying illustrative drawing shows, in elevation with the cover plate removed, a padlock constructed according to the invention.

20 The casing *a* of the padlock is provided with parallel guideways *b* formed conveniently integral therewith and between which there is arranged a slide *a* bolt *c* that is adapted to be held in the normal or locked position by a helical spring *d* housed within 25 a recess *e* of the bolt *c*. One end of the spring bears against one end of the recess *e* and the other end of the spring bears against an appropriate abutment *f* which also serves 30 to limit the travel of the bolt.

The outer solid portion of the bolt *c* can extend as shown across the pathway of a

guided annular link *g*, whose continuity is interrupted at *h* so as to form a gap into which the outer end of the bolt *c* shoots 35 automatically when said gap is brought into register therewith by rotation of the link *g* in the act of locking.

When it is desired to unfasten the padlock by rotation of the link *g* the spring-operated bolt *c* is withdrawn from the gap *h* by a suitable key of ordinary type having a lateral wing turning about the pivot *i* and engaging one or other of the lugs *j* in a manner well understood. The key is indicated in dotted lines at *k*.

What I claim is:—

In a lock, a ring formed with a gap, a casing, curved guides in said casing in which said ring can rotate, a bolt formed with a slot, webs in said casing between which said bolt can slide toward and from said ring, a stop in said casing projecting within the slot of said bolt, a spring between said stop and one end of the slot of said bolt, a pivot 55 for a key in said casing, and arms on said bolt adapted to be engaged by a key turning about said pivot.

Signed at London, England, this eleventh day of November, 1913.

GEORGE HUNT LAMB.
